His Attorney.

UNITED STATES PATENT OFFICE

GORTON R. FONDA, OF SCHENECTADY, NEW YORK, ASSIGNOR TO GENERAL ELECTRIC COMPANY, A CORPORATION OF NEW YORK.

APPARATUS AND PROCESS FOR FRACTIONATING AIR

Application filed September 20, 1918; Serial No. 254,992.

To all whom it may concern:

Be it known that I, GORTON R. FONDA, a citizen of the United States, residing at Schenectady, in the county of Schenectady, State of New York, have invented certain new and useful Improvements in Apparatus and Processes for Fractionating Air, of which the following is a specification.

The present invention comprises a process and apparatus for obtaining concentrates of oxygen, nitrogen and argon from the air.

In my prior Patent No. 1,211,125, I have described a process and apparatus for fractionating air whereby a liquid oxygen-argon mixture is obtained containing about 94 to 96% oxygen, several per cent argon and some nitrogen, and this mixture is rectified to produce commercially pure oxygen and an argon concentrate.

In accordance with my present invention, I have provided a process whereby the argon, instead of remaining in a liquid oxygen residue, is carried away as a gas with nitrogen gas and this mixture is subsequently liquefied and fractionated to concentrate the argon. The difference in temperature in the first step of the fractionation either to cause the argon to remain with the liquid oxygen or to escape with the gaseous nitrogen is only about 0.7° K., but this difference in operation can be secured by a control of the rate of flow of the gases through the apparatus.

Among the advantages of this modified process are:—the recovery from the air of a higher percentage of argon; the production of a nitrogen concentrate of a high degree of purity; the production of an argon concentrate adapted to be more readily purified for commercial use, these advantages being attained with the production of oxygen of the usual high grade of commercial purity.

The accompanying drawing illustrates somewhat diagrammatically one apparatus suitable for carrying out my invention. The apparatus includes the rectification column 1 wherein liquid air is subjected to fractional distillation, and another distillation column 2 wherein the gaseous mixture coming from column 1 is subjected to a second fractional distillation.

I find that when liquid air is subjected to rectification that the residual liquid after this process has been continued for a suffi-

cient length of time consists largely of oxygen, containing only about 1% or less, of other gas, and the gaseous distillate consists largely of nitrogen containing substantially all of the argon from the original air, and incidentally a small percentage of oxygen. The argon and oxygen can be separated from the nitrogen by a re-rectification in a second rectifier yielding a concentrate consisting of oxygen, about 11 to 22% argon, and a little nitrogen.

Referring to the drawing, air compressed in the usual manner above the critical pressure is delivered through a conduit 3 and a coil 4 to an expansion valve 5. The coil 4 preferably is surrounded by previously liquefied air. When the cooled compressed air passes through the expansion valve 5 part of it is liquefied and is conveyed by the conduit 6 to the top of the rectification column 1. The operation of the liquefier may proceed in accordance with the usual well understood practice. Compressed air at the beginning of the operation is expanded through the valve 5, thereby cooling the air. The cooled air descends in the column 1 and surrounds the coil 4. The compressed air thus being precooled issues from the expansion valve at a progressively lower temperature until some of the expanding air is liquefied. After the liquefaction has once been started only enough cooling by expansion need occur to compensate for heat influx through the walls of the column 1.

The liquefied air descends through the perforated baffle plates 7 in contact with the vapors ascending from the liquid at the foot of the column. This liquid is boiled by the latent heat which is liberated by the liquefaction of some of the compressed air in the coil 4. Greater reliance is placed by the operator on chemical analyses of the gases at different points in the column than on temperatures as indicated by thermometers.

However, it may be stated that in this first column the temperatures will range from about 90° K. at the bottom to about 79° K. at the top, the pressure being kept at a few pounds above atmospheric pressure. The rate of flow is adjusted until gaseous nitrogen and argon constituents, containing a small amount of oxygen, leave the column 1. A residue consisting of about 99% oxygen remains at the foot of the column. The gaseous fraction is passed through a conduit 100

- 8 into a compressor 9. This gaseous fraction consists largely of nitrogen and argon and should contain no more than about 2% oxygen. It is conducted from the compressor into the coil 10 at the foot of the rectification column 2. The compressed nitrogen, oxygen, argon mixture is cooled in this coil 10 surrounded by a bath of liquefied gases and the cooled compressed mixture passes through a second expansion nozzle 11, where a second liquefaction of the gas occurs. The liquid is carried through the conduit 12 to the top of column 2 where it descends through the screens 13 in contact with the gases ascending from the boiling liquid at the foot of the column. In the second column the pressure will also be a few pounds above atmospheric pressure and the temperature will range from about 80° K. in the liquid at the bottom to about 77.5° K. at the top of the column, but the exact temperatures will depend upon the percentage of oxygen the operator is willing to leave in the argon concentrate.
- 35 The rectification in this column is regulated to yield substantially pure nitrogen gas through the conduit 14 which may be utilized for fixation processes, or any other industrial use requiring substantially pure nitrogen. The liquid collecting at the foot of the column and escaping through the conduit 15 then consists almost entirely of argon and oxygen with a very small percentage of nitrogen, say, about 2%. This argon concentrate may be given a chemical treatment, as, for example, heating in contact with copper or hydrogen in order to remove oxygen, and may then be used directly for commercial purposes, for example, as a filling in incandescent lamps.
- 40 What I claim as new and desire to secure by Letters Patent of the United States, is:—
1. The process of fractionating air which consists in subjecting liquid air to fractional distillation until a gaseous distillate containing argon as well as nitrogen and oxygen is obtained, liquefying said gaseous distillate and subjecting the resulting liquid to a second fractional distillation, conducting away gaseous nitrogen and retaining a liquid residue consisting largely of oxygen and argon.
  2. The process which consists in fractionating liquid air by distillation until a residue is obtained consisting substantially entirely of oxygen, liquefying the gaseous distillate consisting largely of nitrogen and containing argon and oxygen, fractionating said liquid by distillation to yield gaseous nitrogen and a liquid consisting largely of oxygen and argon.
3. A device for fractionating air to yield substantially pure oxygen and nitrogen and an argon concentrate, which consists of a rectification column, means for introducing liquid air near the top of said column, means for withdrawing oxygen at the foot of said column, a conduit for withdrawing a gaseous distillate near the top of said column, means for liquefying said distillate, and a second rectification column for independently fractionating the resulting liquid to yield substantially pure nitrogen and an argon concentrate.
4. A device for fractionating air to yield an argon concentrate which consists of the combination of means for fractionating air into two portions one of which consists of substantially pure oxygen, the other portion comprising the nitrogen and argon, means for compressing and liquefying said nitrogen-argon portion, a fractionating column, a conduit conveying said liquefied nitrogen-argon portion to said column to the exclusion of said oxygen portion, and a conduit for carrying away a nitrogen concentrate from the top of said column.
5. An apparatus for producing an argon concentrate which consists in means for fractionating liquid air to produce substantially pure oxygen, a conduit for carrying away the gaseous residue consisting largely of nitrogen containing substantially all of the argon, means for liquefying the same, means for fractionating said liquid independently of the oxygen into nitrogen, and an argon concentrate.
6. A process for producing an argon concentrate which consists in rectifying liquid air to produce a substantially pure liquid oxygen, liquefying the gaseous distillate and fractionating the resulting liquid until a residue is obtained containing about 11 to 22% argon, about 2% nitrogen, the balance being oxygen.
- In witness whereof, I have hereunto set my hand this 19th day of September 1918.
- GORTON R. FONDA.
